TELEVISION CABINET OR SIMILAR ARTICLE

Joseph D. Portanova, Arcadia, and John Stevens, Downey, Calif., assignors to Hoffman Radio Corporation, a corporation of California

Application May 11, 1954, Serial No. 30,414

Term of patent 14 years

(Cl. D56—4)

To all whom it may concern:

Be it known that we, Joseph D. Portanova and John Stevens, are respectively a citizen of the United States of America residing at Arcadia, in the county of Los Angeles, State of California, and a citizen of the United States of America, residing at Downey, in the county of Los Angeles, State of California, have invented a new, original, and ornamental Design for a Television Cabinet or Similar Article, of which the following is a specification, reference being had to the accompanying drawings, forming a part hereof:

Figure 1 is a front elevational view of a television cabinet or similar article showing our new design;

Figure 2 is a top plan view thereof; and

Figure 3 is a side elevational view thereof.

The rear of the cabinet is plain and unornamented.

The essential features of our design reside in those portions shown in full lines.

We claim:

The ornamental design for a television cabinet or similar article, substantially as shown and described.
